By Arthur F. Durand
Atty.

UNITED STATES PATENT OFFICE

53 GEORGE H. REIMER, OF FULTON, ILLINOIS, ASSIGNOR TO PATENT NOVELTY COMPANY,
OF FULTON, ILLINOIS, A CORPORATION OF ILLINOIS

LATCH LOCK

63 Application filed November 8, 1928, Serial No. 317,886. Renewed March 23, 1932.

This invention relates to latch mechanism having key-operated instrumentalities, and having also a handle by which to open and close the door, or other closure, to which the mechanism is applied.

Generally stated, the object of the invention is to provide a novel and improved construction whereby the reciprocating latch member, having a beveled strike portion, is provided with a handle by which it can be reciprocated to unlatch the door, or other closure, and having a key-operated lock mechanism for locking the latch member in locked position, operative, when in unlocked condition, to permit free movement of said latch member by means of said handle.

It is also an object to provide certain details and features of construction and combinations tending to increase the general efficiency and desirability of a lock-controlled latch mechanism of this particular character.

To the foregoing and other useful ends, the invention consists in matters hereinafter set forth and claimed and shown in the accompanying drawing, in which—

Figure 1 is a front elevation of a mail box provided with a door having a latch lock mechanism involving principles of the invention;

Figure 2 is a perspective of the said latch lock mechanism;

Figure 3 is a horizontal section, on a larger scale, on line 3, 3 in Figure 1;

Figure 4 is a detail face view of said mechanism, with a portion of the casing thereof removed, and showing certain portions broken away, for convenience of illustration, showing the lock mechanism in unlocked position;

Figure 5 is a similar view showing the lock mechanism in locked position;

Figure 6 is a vertical section on line 6, 6 in Figure 3, showing the key inserted;

Figure 7 is a detail view of one of the parts of said mechanism.

As thus illustrated, the invention is shown applied to the door 1 of an ordinary mail box 2 of any suitable or desired character. 50 It will be understood, however, that the in-

vention can be used on a door or closure of any suitable character, or for any desired purpose.

The latch lock mechanism, as shown, comprises a casing formed of a front plate 3 and a box-like rectangular housing 4 secured to the back of this plate by means of lugs 5 inserted through slots in the plate and riveted over in any suitable or desired manner. Within said housing, there is a rotary disk-like member 6 provided with a slot or key-hole 7 therein, and provided also with diametrically opposite peripheral notches 8 and 9 for engaging a spring 10, secured in position, as shown in Figures 4 and 5 of the drawing. 60 The front plate 3 has a key-hole slot 11 having its center portion 12 enlarged to form, in effect, an annular opening in which the reduced portion 13 of the key 14 can rotate, while the reduced end portion 15 of 70 said key is adapted to rotate in the round hole 16 formed in the back of the box-like housing 4 of the casing. When the key is fully inserted, it will be seen that its wing portions 17 are in the slot 7, previously mentioned, whereby rotation of the key will cause rotation of the member 6 in the desired manner. A key-hole guard 18 is mounted to rotate in the opening 19 formed in the front wall 20 of the door 1, and is provided with 75 a straight key hole slot 21 for the insertion of the key, and this guard 18 rotates with the key. The reciprocating latch member 22 is substantially rectangular and is provided with a bent or bevel-shaped strike portion 23, the bevel of which latter is adapted to strike the edge portion 24 of the front wall of the mail box when the door is closed, thus reciprocating the member 22 to the right within the housing 4 of the casing. A spring 25 80 normally and yieldingly holds the latch member 22 in the position shown in the drawing, but is adapted to yield when the latch member is forcibly moved to the right, as by grasping the handle 26, which is rigid with said strike portion 23, when it is desired to unlatch the door. 85

When the parts are in the position shown in Figure 4, the door can be unlatched by means of said handle 26, and by moving the 100

member 22 to the right. However, when the parts are in the position shown in Figure 5, it will be seen that unlatching the door is not possible, as at such time the pin 27 on the 5 disk 16 is in engagement with the angular shoulder 28 formed on the member 22, whereby the latter is held against displacement. Therefore, to unlock the latch member so that it may be shifted to unlocked position, so that 10 the door may then be pulled open by means of the handle 26, it is necessary to insert the key and rotate the disk 16 to the position shown in Figure 4 of the drawing, for at such time the pin 27 is at the other side of 15 the key-hole, and this leaves the member 22 free to be shifted in position to unlock the door.

The latch mechanism can be secured to the 20 inside of the door 1 in any suitable or desired manner, as by the use of the rivets inserted through the holes 29 in the plate 3 and through the door itself.

With the foregoing construction, which is 25 illustrative of one form of the invention, it will be seen that the latch member and its strike portion 23 are freely movable into unlocked position, by means of the handle 26, when the lock mechanism is in unlocked condition. In such condition, the key 14 is not 30 necessary for the opening and closing of the door. However, to prevent opening of the door, it is only necessary to insert the key and rotate the member or disk 16 one hundred and eighty degrees to the position shown in Figure 5 of the drawing, and in such condition the latch mechanism cannot be operated to 35 unlatch the door. In this position the key may be withdrawn through the key hole. Thus, to unlatch the door, both the key 14 and the handle 26 are necessary, as the key is 40 only operative to operate the lock mechanism, and it is not operative to shift the latch member. By having the key and lock mechanism rotate one hundred and eighty degrees, the key 45 is withdrawable without rotation in either the locked or unlocked position of said mechanism.

It will be seen that the latch plate member comprising the portions 22 and 23 is substantially U-shaped in form, being turned on its 50 side to slide back and forth on its lower edge, so that it reciprocates in the plane thereof. The member 6 is disposed immediately back of the latch plate member, with means thereon to engage the latch plate member, thereby 55 to control the latter in the manner shown and described.

What I claim as my invention is:

1. In latch-lock mechanism for a swinging door, the combination of a reciprocating latch member, a handle for operating said latch member into unlatched position, reciprocating therewith, a spring for operating said member into latched position, stationary 60 strike means for engaging said latch member

when the door is closed, operative when the door is being closed to shift said member and handle into unlatched position, rotary lock mechanism operable by a removable key for locking said member in latched position, operable into unlocking position while said member remains in latched position, and fixed means forming a key hole through which said key is insertable in engagement with said mechanism, said key and mechanism being rotatable forward one hundred and eighty degrees into locking position, or backward into unlocking position, to permit withdrawal of the key in either of said positions through said key hole, said lock mechanism comprising a rotatable member having diametrically opposite peripheral notches, a spring for engagement alternately with said notches, said rotatable member having a key-hole slot to receive the key, and having also a projection disposed in position to prevent displacement of said latch member when one of said notches is engaged by said last-mentioned spring, and which projection is disposed in position to prevent interference with free displacement of said latch member when the other notch is engaged.

2. In latch-lock mechanism for a swinging door, the combination of a reciprocating latch member, a handle for operating said latch member into unlatched position, reciprocating therewith, a spring for operating said member into latched position, stationary strike means for engaging said latch member when the door is closed, operative when the door is being closed to shift said member and handle into unlatched position, rotary lock mechanism operable by a removable key for locking said member in latched position, operable into unlocking position while said member remains in latched position, said lock mechanism comprising a rotatable member having diametrically opposite peripheral notches, a spring for engagement alternately with said notches, said rotatable member having a keyhole slot to receive the key, and having also a projection disposed in position to prevent displacement of said latch member when one of said notches is engaged by said last-mentioned spring, and which projection is disposed in position to prevent interference with free displacement of said latch member when the other notch is engaged.

3. In lock mechanism, the combination of a casing, a reciprocating latch plate member disposed in position within the casing, adapted to reciprocate in the plane thereof, within said casing, having a manually operable outer engaging portion, a flat control plate disposed flatwise against the back of said latch plate member, within said casing, and controlling means on one plate extending into the plane of the other plate, said control plate being adapted to be operated by a key to control

said latch plate member and thereby lock and unlock the latch plate member, the casing wall back of said control plate having a round hole to pivot the end of said key.

5 4. A structure as specified in claim 3, said latch plate member being substantially U-shaped, being turned on its side to slide on one lower edge thereof, said engaging portion having a handle for the reciprocation 10 of said latch plate member in the plane thereof.

15 5. A structure as specified in claim 3, including a spring engaging said control plate, said casing having a key hole through which said key may be inserted through the gap of said U-shaped plate, into engagement with said control plate, and the back of said casing having a round hole to engage the end of said key.

20 6. A structure as specified in claim 3, said latch plate member being substantially U-shaped, being turned on its side to slide on one lower edge thereof, whereby the two plates operate close together in parallel 25 planes, one behind the other, and spring means engaging and controlling said plates, said latch plate member having portions serving as stops to limit the operation thereof, and said control plate having stop means 30 thereon to limit its operation.

7. In lock mechanism, the combination of a casing, a reciprocating latch plate member disposed in position within the casing, adapted to reciprocate in the plane thereof, within 35 said casing, having an engaging portion, a flat control plate disposed flatwise against the back of said latch plate member, within said casing, and means on said control plate for engaging and controlling said latch plate 40 member, said control plate being adapted to be operated by a key to control said latch plate member and thereby lock and unlock the latch plate member, the casing wall back of said control plate having a round hole 45 to pivot the end of said key, said latch plate member being substantially U-shaped, being turned on its side to slide on one lower edge thereof, said engaging portion having a handle for the reciprocation of said latch plate 50 member in the plane thereof.

8. In lock mechanism, the combination of a casing, a reciprocating latch plate member disposed in position within the casing, adapted to reciprocate in the plane thereof, within 55 said casing, having an engaging portion, a flat control plate disposed flatwise against the back of said latch plate member, within said casing, and means on said control plate for engaging and controlling said latch plate 60 member, said control plate being adapted to be operated by a key to control said latch plate member and thereby lock and unlock the latch plate member, the casing wall back of said control plate having a round hole 65 to pivot the end of said key, including a

spring engaging said control plate, said casing having a key hole through which said key may be inserted through the gap of said U-shaped plate, into engagement with said control plate, and the back of said casing 70 having a round hole to engage the end of said key.

Specification signed this fifth day of November, 1928.
